AXLE PULLER

Harold B. Comer, Box 151, Elkton, Va.

Filed Feb. 29, 1960, Ser. No. 11,581

3 Claims. (Cl. 29—254)

This invention relates to pulling tools in general, and in particular to tools used to pull automobile axles from their housings. This application is a continuation-in-part of my application filed May 1, 1958, Serial No. 732,316, and now abandoned.

Axle pullers have been known and used for some time. The conventional puller consists of a rod, or shaft, with a knob on one end and means for coupling to the axle to be pulled at the other end. A hammer is slidably mounted upon the shaft so that it may be moved along the shaft to forcibly strike the knob to exert a pulling force upon the axle. On some cars the axles have flanges at their ends, and it is necessary to connect the puller to the axle studs on the axle flange, and on others the axles have nuts on their ends and there must be some means to engage behind the nut which is threaded upon the axle end. Different cars have the axle studs positioned different radial distances from the axle. These wide variations have made it necessary for a repair shop operator to stock a number of axle pullers having different means for coupling to the axle in order to be able to remove axles from cars of all makes. This is expensive and adds to tool storage problems.

The principal object of the present invention is to provide an axle puller which will be capable of pulling axles of many different make cars, even though the coupling means varies.

Another object of the invention is to provide a tool which will be connectible to the axle studs of all vehicles, irrespective of the radial spacing of the studs, and can be converted to connect to an axle having a nut on its end.

A further object is to provide another form of tool which has a combination coupling head making it applicable universally to different makes of cars without need for a conversion operation.

Other objects of the invention will become apparent from the following description of practical embodiments thereof when taken in conjunction with the drawings which accompany, and form part of, this specification.

In the drawings:

FIGURE 1 is a side elevational view of a puller tool embodying the principles of the present invention, shown attached to an axle, in position to pull the axle;

FIGURE 2 is a sectional view taken on line 2—2 of FIGURE 1, showing the hammer element of the pulling tool;

FIGURE 3 is a sectional view taken on the line 3—3 of FIGURE 1, illustrating the coupler head attached to the axle studs on the axle flange;

FIGURE 4 is a sectional view taken on the line 4—4 of FIGURE 3;

FIGURE 5 is a view similar to FIGURE 3 with an adapter attachment fastened to the coupler head;

FIGURE 6 is a sectional view taken on line 6—6 of FIGURE 5;

FIGURE 7 is a sectional view taken on line 7—7 of FIGURE 6;

FIGURE 8 is a sectional view taken on line 8—8 of FIGURE 7;

FIGURE 9 is a view similar to FIGURE 4, illustrating a modified form of the device;

FIGURE 10 is a perspective view of a combination coupling head adapted to fit all cars;

FIGURE 11 is a rear elevation of the head shown in FIGURE 10, the tool rod, or shaft, carrying the head being shown in section;

2

FIGURE 12 is a section through the head taken on the line 12—12 of FIGURE 11; and

FIGURE 13 is a bottom plan view of the combination coupler head.

5 In general, the invention concerns an axle puller which has a coupler head that will receive the axle studs of different makes of cars irrespective of their radial spacing from the axle axis, and has provision to receive an adapter, or integrally incorporates means, for coupling to an axle having a nut on its end, to provide a tool which can be used to remove axles from all makes of cars.

10 Referring in detail to the drawings, and first advertiring to that form of the invention illustrated in FIGURES 1 to 8, there is shown an axle puller, generally designated 1, which comprises a rod, or shaft, 2 having a knob 3 at one end and being screw-threaded, as at 4, at the other end. A coupler head 5 having an internally threaded boss 6 is screwed upon the end 4 of the rod.

15 A cylindrical hammer 7 having an axial bore 8 is slidably mounted on the rod 2. A pair of diametrically extending handles 9 provide means by which the operator can grasp the hammer and slide it along rod 2 to strike against the knob 3 and drive the puller in the direction of the knob to pull an axle.

20 The coupler head 5 consists of a hub 10, coaxial with the boss 6, from which securing arms 11, 12 and 13 project. The arms lie in a common plane normal to the axis of the hub, and are angularly spaced from one another as required to overlie axle stud positions on the axle flange 14. An automobile axle flange is provided with five axle studs 15, arranged in a circle about the flange axis and equally spaced apart. The studs lie along radii of the flange spaced apart angular distances of 36°. Arms 11 and 12 have central slots 16 and 17, elongated radially of the arms and spaced equidistant to the angular spacing of the axle studs. Arm 13 has a slot 18 elongated radially coincident with the extended bisector of the angle formed by the slots 16 and 17. 25 Thus, the slots of the three arms will receive axle studs arranged angularly as described and at different radial distances from the axle flange center. The coupler head is recessed at its center, as at 19, on the side opposite the boss to receive the axle end under certain conditions, as will be described.

30 In order to permit attachment of an adapter to the head to couple to axles which do not have a flange type axle, the arm 13 of the coupler head is wider than the other arms, with the wider portion offset to one side of the slot 18 to permit the provision of a hole 20, diametrically opposed to the slot 16 in arm 11. An adapter 21, in the form of a central cap 22 with diametrically projecting arms 23, is provided to overlie the center of the coupler head and be attached to it. The arms 23 are apertured, as at 24, to receive bolts 25 which pass through slot 16 in arm 11 and the opening 20 in arm 13. The cap portion of the adapter is cup-shaped, and has a notch 26 entering from one side wall and projecting at least to the center of the cap. The cap wall around the notch 26 provides a pulling flange 27.

35 When the tool is to be used to pull an axle provided with a flange 14, as shown in FIGURES 1, 3 and 4, the adapter 21 is not used. The coupler head is placed against the axle flange with the axle studs 15 projecting through the slots 16, 17 and 18 of the coupler head arms. Nuts 28 are then threaded on the studs to secure the coupler head in place. As the axle puller and axle are now coupled together, repeated blows by the hammer against the knob 3 will pull the axle 29 from its housing 30.

40 If an axle such as that shown in FIGURE 6 is to be pulled, the adapter 21 is secured to the coupler head by

bolting through the openings 24, slot 16 and hole 20. The axle 31 then has a nut 32 threaded on its end, and the notch of the adapter is slipped over the axle so that the nut is within the adapter cap portion and the flange 27 lies behind the nut. The end of the axle projects into the recess 19 in the coupler head. It will be clear that the impact force of the tool hammer will be imparted through the adapter flange against the back of the nut to exert a pulling force upon the axle.

In FIGURE 9, there is shown a head 33 similar to head 5. It is also provided with an internally-threaded boss 34 similar to boss 6. However, instead of a direct engagement between the rod and boss as in the form shown in FIGURES 1 through 8, the rod 35 is of somewhat narrower diameter than rod 2 and its threaded end 36 is engaged within an internally-threaded reducer 37 which is provided with an externally-threaded stem 38. The 38 is threadedly engaged within boss 34. This type of construction permits use of a narrower rod with a standard size coupler head while maintaining a strong and secure attachment between the rod and head.

A combination coupler head 39 is shown in FIGURES 10 through 13, which is designed to perform the functions of both the coupler head and the adapter previously described. In this form of the invention the head is composed of a cup 40 and a mounting plate 41, with the cup and mounting plate being integral.

The cup 40 has a cylindrical wall 42, a closed bottom 43 and an open end 44. A notch 45 is cut into the wall of the cup from the open end to the bottom. A boss 46 projects from the bottom of the cup and is threaded to receive the end of rod 47.

Plate 41 has a circular central section 48 which overlies the open end of the cup, and three radially projecting arms 49. Each arm is slotted, and the slots 50 are elongated radially of the plate. The slots and arms are arranged in the same relative angular positions as in the form first described. The central portion of the plate is notched, as at 51, between two of the arms, with the notch extending radially of the plate. The notch in the plate has its center line (which is a radius of the plate) lying in a radial plane which is common to the plate and the cup, and which also includes the longitudinal centerline of the notch 45 in the cup. The plate notch is narrower than the cup notch so that the side walls of the cup forming the edges of the cup notch are spaced outwardly from the edges of the plate notch providing shoulders 52 at either side. This construction will allow the notch 51 in the plate to pass over an axle while a nut on the axle will pass through the cup notch 45 and the nut will bear against the shoulders 52. Thus, the plate will form the bearing member for the nut when pulling an axle having a nut on the end, as well as a central support for the slotted arms which are to connect to an axle having a flange with axle studs.

It is believed that the operation of the puller having the modified coupler head will be clear from the above description, and that no further statement of the operation need be given.

While in the above practical embodiments of the invention have been disclosed, it will be understood that the details of construction described and shown are merely by way of illustration, and the invention may take other forms within the scope of the appended claims.

What is claimed is:

1. An axle puller of the type including a rod having a hammer slidably mounted thereon with a knob at one end of the rod against which the hammer may be struck and a coupler head at the other end of the rod for connection to an axle to be pulled, the improvement which comprises, the coupler head including an integrally joined cup and plate with the plate overlying the mouth of the cup and forming within the cup a closed chamber, a notch in the plate extending from the edge radially to the center, a notch in the cup opening to the chamber of greater width than the notch in the plate registering with and centered with respect to the plate notch, whereby the coupler head can be placed over an axle having a nut on the end and the axle will pass into the notch in the plate and the nut will pass through the notch in the cup and into the chamber to bear upon the plate on either side of the plate notch when the coupler head is moved lengthwise of the axle, said plate having a plurality of slots therein exteriorly of the periphery of the cup, the slots being elongated radially of the plate and lying along radii of the plate which are angularly related in conformity to the angular relationship of radii passing through axle studs on a flange carried by an axle to be pulled, whereby axle studs arranged on flanges in circles of various diameters may be received in the slots of the coupler head.

2. An axle puller as claimed in claim 1 wherein the plate has a central hub portion overlying the mouth of the cup and having said plate notch therein, and a plurality of arms projecting radially from the central hub portion and containing said slots.

3. An axle puller as claimed in claim 2 wherein the coupler head has a boss projecting from the cup portion at the end remote from the plate, and the boss is recessed to receive the end of said rod.
